UNITED STATES PATENT OFFICE.

HENRY L. BARTON, OF GARY, INDIANA.

EXCAVATOR.

1,416,938.

Specification of Letters Patent. Patented May 23, 1922.

Application filed May 9, 1919. Serial No. 295,398.

To all whom it may concern:

Be it known that I, HENRY L. BARTON, a citizen of the United States, and a resident of the city of Gary, county of Lake, and State of Indiana, have invented certain new and useful Improvements in Excavators, of which the following is a specification.

My invention relates to improvements in excavators, and has for its object the provision of an improved construction of this character capable of a number of uses, which is of simple construction and efficient in operation.

Other objects will appear hereinafter.

The invention consists in the combinations and arrangements of parts hereinafter described and claimed.

The invention will be best understood by reference to the accompanying drawings forming a part of this specification, and in which,

Fig. 1, is a side view of an excavator embodying the invention, shown in one position of use,

Fig. 2, an enlarged detail section taken through the boom of said excavator,

Fig. 3, a top plan view corresponding with Fig. 1,

Fig. 4, an enlarged longitudinal section taken through the conveyor employed in the excavator,

Fig. 5 a top plan view of said conveyor shown detached,

Fig. 6, a view similar to Fig. 1, but showing a modified form of construction,

Fig. 7, an enlarged detail view of the conveyor shown in Fig. 6,

Fig. 8, an end view of the conveyor shown in Fig. 6,

Fig. 9, a top plan view of the excavator shown in Fig. 6, and

Fig. 10, a top plan view of the conveyor shown in Fig. 6.

The form of construction illustrated in Figs. 1 to 5, inclusive, comprises a suitable boom 11, pivotally mounted, in the usual way, on a suitable truck 12 for swinging vertically and horizontally in the usual manner. The boom 11 is formed of two oppositely arranged channel irons positioned with their open sides facing inwardly or toward each other, and connected together at their upper sides by means of a suitable lattice-work 13 to form a strong and rigid construction. Tracks in the form of angle irons 14 are secured to the inner faces

of said channel irons, and a carriage 15 is mounted upon rollers or wheels 16 mounted to travel upon the tracks 14, as shown. A conveyor, in the form of an excavating scoop 17 is suspended, at one end, by means of hangers 18, from a cross bolt 19 mounted on carriage 15 below the boom 11. The carriage 15 carries depending rigid stop arms 20 contacting with one wall of the conveyor 17 to limit the swing of said conveyor on the pivot bolt 19 in one direction. At its other end the conveyor 17 carries guide rollers 21 running upon the under sides of the channel iron sides of the boom 11 and serving to limit the swing of said conveyor in the other direction. Upwardly extending guide arms or fingers 22 are also provided to co-operate with the rollers 21 to prevent the same from running off of the channel irons of the boom 11. Grooved guide pulleys 23 and 24 are mounted respectively on the carriage 15 and on the cross bolt which holds the rollers 21 and serve as a means for guiding a cable 25 secured to the outer end of the conveyor 17, said cable being also extended over suitable guide pulleys on the boom 11, as indicated. Another cable 26 is secured to a bail 27 at the inner end of the conveyor 17, and also extends over suitable guide pulleys on the boom 11, said cables 25 and 26 extending respectively to drums 28 and 29 on the truck 12, which are operable from said truck in the usual manner for manipulating the conveyor 17 and causing the same to travel to and fro on the boom 11, as will be readily understood. The conveyor 17 has one portion of its bottom formed into a serrated scraper blade 30, and the other portion thereof formed into a hinged trap door 31 normally held in closed position by means of a spring-held trigger 32 connected with a suitable cable 33 extending over suitable guide pulleys on the boom 11 and leading to the truck 12, as indicated, and whereby the bottom portion 31 may be tripped when desired to dump the contents of the scoop conveyor 17. By this arrangement it will be observed that the scoop conveyor 17 may be readily manipulated along the boom 11, as desired, to scoop up and discharge the earth in digging or filling trenches or the like. It will be observed that the cutting or scooping force is applied directly to the front or cutting end of the conveyor scoop and whereby

the construction is greatly simplified and the necessity for great strength in the connections between the scoop and the carriage is obviated. This arrangement also automatically holds the rollers 21 in contact with the under side of the boom. The construction is shown in Fig. 1 as employed in filling a trench, by scooping the excavated earth thereinto, and it will be observed that 5 the boom holds and guides the scraper conveyor in its work, providing a definite path of travel therefor and compelling the positive operation thereof. Likewise, it will be observed that by adjusting the boom 11 to 10 various inclinations, a trench may be dug with the scoop conveyor 17. Also, when desired, the conveyor 17 may be reversed on the boom and operatively employed in the opposite direction, to fill or dig a trench in 15 working away from the truck instead of toward it, as indicated in Fig. 1. This may be accomplished by disconnecting the cables and removing the bolt 19, whereupon the conveyor or scoop 17 may be readily reversed 20 in position and the cables re-connected with corresponding parts.

In the construction illustrated in Figs. 6, 7, 8, 9 and 10, a lighter boom construction 34 is employed, and a somewhat different 25 truck construction 35 is indicated. Also, a slightly different form of carriage is shown arranged to travel upon the boom 34, and the conveyor 37 is shown in the form of a rigid scraper. Suitable cables are provided, as indicated, for manipulating the boom and the scraper conveyor 37, and it is thought that the operation of this device will be readily understood from the illustrations. This form of device is a simpler 30 form than the one already described, and is consequently capable of more economical manufacture, although not capable of such a wide variety of uses.

While I have illustrated and described 40 the preferred forms of construction for carrying my invention into effect, these are capable of variation and modification without departing from the spirit of the invention. I, therefore, do not wish to be limited 45 to the precise details of construction set forth, but desire to avail myself of such variations and modifications as come within the scope of the appended claims.

Having described my invention, what I 50 claim as new and desire to secure by Letters Patent is:—

1. An excavator comprising a boom; a wheeled carriage mounted to travel on said boom; a scoop conveyor pivotally mounted 55 at its rear end on said carriage; a guide roller at the forward end of said scoop resting loosely against the under side of said boom; an operating cable connected directly with the forward end of said scoop to draw 60 said scoop through its operative movement;

and an operating cable operatively connected to draw said scoop through its inoperative movement, substantially as described.

2. An excavator comprising a boom; a wheeled carriage mounted to travel upon 70 said boom; a scoop conveyor pivotally mounted at its rear end on said carriage; a guide roller at the forward end of said scoop resting loosely against the under side of said boom; guide fingers operatively connected with said scoop and loosely embracing the sides of said boom; and means for reciprocating said scoop, substantially as described.

3. An excavator comprising a boom; a 80 wheeled carriage mounted to travel upon said boom; a scoop conveyor pivotally mounted at its rear end on said carriage; a guide roller at the forward end of said scoop resting loosely against the under side 85 of said boom; guide fingers operatively connected with said scoop and loosely embracing the sides of said boom; an operating cable connected directly with the forward end of said scoop to draw said scoop through 90 its operative movement; and an operating cable operatively connected to draw said scoop through its inoperative movement, substantially as described.

4. An excavator comprising a boom, said 95 boom consisting of two channel irons arranged with their open sides facing inwardly; a lattice-work connecting the upper sides of said channel irons; a track in the form of an angle iron secured to the inner 100 face of each of said channel irons; a carriage mounted upon rollers mounted to travel on said track; a conveyor scoop having one end pivotally suspended on said carriage; a stop on said carriage limiting the swing of said conveyor in one direction; rollers on the other end of said conveyor contacting with the bottoms of said channel irons to limit the swing of said conveyor in the other direction; a hinged bottom for said conveyor; 105 a trigger normally holding said bottom closed; a flexible cable for tripping said trigger to release said bottom; and cables and guide pulleys on said boom, said cables being connected with said conveyor for moving said conveyor and carriage to and fro along said boom, substantially as described.

5. In an excavator, the combination of a boom having guideways secured thereto; a pivotally mounted scoop conveyor mounted on said guideways; guide rollers mounted on one end of said scoop and engaging the under side of said boom; guide means co-operating with said rollers for retaining said scoop on said guideways; and a plurality of 110 operating cables for reciprocating said scoop to and fro on said guideways, substantially as described.

6. In an excavator, the combination of a boom having guideways secured thereto; a 115

carriage mounted on said guideways; a scoop conveyor pivotally mounted on said carriage; guide members operating with said scoop and loosely embracing the sides thereof; guide means mounted on said scoop and engaging the under side of said boom; guide members co-operating with said guide means for retaining said scoop on said guideways; and operating cables connected to said scoop 10 at its front and rear ends for reciprocating said carriage to and fro on said guideways, substantially as described.

7. In an excavator, the combination of a boom having guideways secured thereto; a reciprocating carriage mounted on said guideways; a scoop conveyor pivotally mounted on said carriage; guide fingers mounted on said scoop and loosely embracing the sides of said boom; a serrated 20 scraper blade integrally formed on said scoop; and an operating cable connected to said scoop to draw said scoop through its operative movement, substantially as described.

25 8. An excavator comprising a boom formed from oppositely arranged channel members rigidly connected together; a guideway secured to the inner side of each of said guide members; a scoop conveyor mounted on said guideways; guide means loosely embracing said channel members for preventing a lateral movement of said scoop; a serrated scraper blade integrally formed on said scoop; and operating cables connected to 35 said scoop to draw said scoop through its operative and inoperative movement, substantially as described.

9. An excavator comprising a boom formed from channel members rigidly fixed together; a carriage mounted on said boom; a scoop conveyor pivotally mounted on said carriage; guide means loosely embracing said boom and said scoop; a serrated scraper

blade integrally formed on the rear portion of said scoop; a trigger held trap door 45 hingedly mounted on said blade; means for tripping said trigger; an operating cable connected to said scoop to draw said scoop through its operative movement; and a cable connected to said scoop to draw said 50 scoop through its inoperative movement, substantially as described.

10. An excavator comprising a boom; an 55 nular shaped tracks secured to said boom; a roller carriage mounted on said tracks; a scoop conveyor pivotally mounted on said carriage; a guide member mounted on said carriage and loosely embracing the sides of said scoop; rollers mounted on the rear end of said scoop and engaging the under surface 60 of said boom; guide members co-operating with said rollers and loosely embracing the sides of said boom; and cables connected directly to said scoop arranged to draw said scoop through its operative and inoperative 65 movement, substantially as described.

11. In an excavator, the combination of a boom having guideways, of a reciprocating scoop conveyor mounted on said guideways; and guiding means operating with said 70 scoop loosely embracing the sides of said scoop and said boom, substantially as described.

12. In an excavator, the combination of a boom having a reciprocating scoop conveyor 75 mounted thereon, of a serrated scraper blade; and guide members operating with said scoop loosely embracing said scoop and said boom, substantially as described.

In testimony whereof I have signed my 80 name to this specification in the presence of two subscribing witnesses.
